(57) **CLAIM**

The ornamental design for a container for fasteners, as shown and described.

DESCRIPTION

FIG. 1 is a perspective view of a container for fasteners showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a perspective view thereof, shown with the lid in an opened condition; and,

FIG. 9 is a perspective view thereof, shown in a stacked condition.

The broken lines shown are for environmental purposes only and form no part of the claimed design.
